(57) **CLAIM**

The ornamental design for a dental instrument handle, as shown and described.

DESCRIPTION

FIG. 1 is a front plan view of the dental instrument handle; FIG. 2 is a first side plan view thereof; FIG. 3 is a rear plan view thereof; FIG. 4 is a top end view thereof, where the broken lines showing portions of the dental instrument handle are included for illustrating environmental structure and form no part of the claimed design; FIG. 5 is a bottom end view thereof; FIG. 6 is a top end perspective view thereof; and, FIG. 7 is a bottom end perspective view thereof.
